UNITED STATES PATENT OFFICE.

CHRIST J. SCHULTZ, OF MERRILL, IOWA.

DESIGN FOR A RAILWAY-SPIKE.

SPECIFICATION forming part of Design No. 33,170, dated September 4, 1900.

Application filed June 18, 1900. Serial No. 20,775. Term of patent 7 years.

To all whom it may concern:

Be it known that I, CHRIST J. SCHULTZ, a citizen of the United States, residing at Merrill, in the county of Plymouth and State of Iowa, ⁵ have invented and produced a new and original Design for Railroad-Spikes, of which the following is a specification, reference being had to the accompanying drawings, forming a part thereof.

10 Figure 1 is a side elevation of my invention. Fig. 2 is an elevation of the opposite side of my invention, and Fig. 3 is a plan view of the head.

15 As shown in the drawings, the leading or material feature of my design consists of a cylindrical body portion *a*, tapering to a point and provided with a series of teeth at one side.

20 My design comprises a cylindrical body portion *a*, which is tapered downwardly to form a point *b*. Formed upon the body portion *a* are a number of teeth *c*, commencing at a point near its base, arranged one above another and continuing upwardly about one-
25 half the height of the said body portion. The

lower side of each tooth is beveled to lie at an acute angle to the longitudinal axis of the spike and the upper side of each tooth is flat to lie at right angles to the said axis. Each tooth is sharpened at its front and one side ³⁰ edge, the opposite side edge being flat, as shown. Upon the upper end of the body portion *a* is formed a head *d*, having three straight sides *e* and a curved side *f*. The side of the body portion *a*, opposite to that upon ³⁵ which the teeth are formed, is curved longitudinally.

Having now fully shown and described my invention, what I claim as new, and desire to secure by Letters Patent, is—

40 The design for a railroad-spike, as herein shown and described.

In testimony whereof I have signed my name to this specification in the presence of two subscribing witnesses.

CHRIST J. SCHULTZ.
